THEODORE J. FISCHER, OF CHICAGO, ILLINOIS, ASSIGNOR TO STEWART-WARNER SPEEDOMETER CORPORATION, OF CHICAGO, ILLINOIS, A CORPORATION OF ILLINOIS.

TACHOMETER-MAGNET AND MOUNT FOR THE SAME.

1,155,346.

Specification of Letters Patent.

Patented Oct. 5, 1915.

Application filed October 1, 1914. Serial No. 864,523.

To all whom it may concern:

Be it known that I, THEODORE J. FISCHER, a citizen of the United States, residing at Chicago, in the county of Cook and State 5 of Illinois, have invented new and useful Improvements in Tachometer-Magnets and Mounts for the Same, of which the following is a specification, reference being had to the accompanying drawings, forming a part 10 thereof.

The purpose of this invention is to provide an improved construction of tachometer magnet and mount for the same adapted to carry and having associated with it, a calibrating or a temperature compensating shunt 15 or both.

It consists in the elements and features of construction shown and described as indicated in the claims.

20 In the drawings, Figure 1 is a perspective view of a magnet and its mount embodying this invention. Fig. 2 is a direct top plan view of the same. Fig. 3 is an axial section of the line, 3—3, on Fig. 2. Fig. 4 is a 25 section of the line, 4—4, on Fig. 2. Fig. 5 is a section of the line, 5—5, on Fig. 3.

The magnet shown in the drawings is of the split-ring type, that is, one which is formed in the shape of a ring with the 30 poles brought near together leaving a narrow gap or split between them, and designed to be mounted for rotation about its axis. One purpose of the construction is to make the magnet and all parts directly 35 associated with it in the simplest form possible and so as to occupy minimum space in the casing in which it is mounted, as a part of a tachometer; and for that purpose the mount, which is necessarily of non-magnetic metal, is constructed so as not to protrude in any direction beyond the surface 40 of the magnet itself.

The magnet, 1, having its central aperture, 1^a, communicating with the gap or split, 45 1^b, between the magnet poles, is completely occupied by the mount, 2, which is a unitary member made of non-magnetic metal, comprising the circular portion which occupies the circular central opening of the magnet, and a spur or tang, 2^a, extending therefrom occupying the split or gap between the 50 magnet poles. By this means the mount and magnet are made relatively non-rotatable without the necessity of providing any

means for securing the one to the other, the 55 tang, 2^a, engaging the gap, 1^b, serving the purpose of securing them together for rotation. The mount is designed to be made of such size as to make a drive fit in the central aperture of the magnet, and it may be 60 slightly upset, if necessary, still further to insure its rigidity with the magnet. The mount has a steel or other hard metal stem or spindle, 3, rigid with said mount at the center thereof, being preferably driven tight 65 thereto; this spindle being hollow from the upper end nearly to the lower end for the purpose of accommodating the spindle of the drag element, not shown in the drawings, whose lower end is stepped in the bearing, 3^a, at the bottom of the cavity of said spindle. On the under or back-side of the magnet, that is, the side from which the spindle, 3, projects, there is mounted a calibrating shunt plate, 4, which is a thin steel 70 member held firmly to the under-side of the mount by means of a shoulder, 3^b, on the spindle, between which and the shunt, 4, a washer, 50, may be interposed, merely for increasing the area of bearing upon the 75 shunt when the spindle is driven tightly into the mount. By this means the shunt, 4, is held very tightly against the under-side of the mount and with its segmental end or head, 4^c, pressed closely against the side of 80 the magnet, lapping usually both its poles, but always lapping one pole, and in position so that by a little movement about the spindle it may lap the other pole more or less. It is held so tightly that no movement 85 can possibly occur during the operation of the instrument; but it is possible by using a proper tool to press against it at either edge forcibly enough to turn it about the spindle, to vary the relative amount of lap 90 on the two poles, thereby varying the amount of magnetic flux which it will carry 95 from pole to pole across the gap, this being the method by which the calibration of the instrument is effected, in original construction. Upon the other side of the magnet there is pivoted to the mount, 2, a temperature compensating shunt plate, 5. The pivot 100 of this plate to the mount is preferably at the opposite side of the spindle from that at which the magnet poles are situated, and the shunt extends from its pivot, lying closely against the side of the mount, to the 105

poles, upon which it laps laterally, always lapping upon one pole and adapted to lap more or less on the other according to the adjustment of its position which is to be effected by the thermostatic device, which will be described. Since this shunt, pivoted and extending as described, must extend across the axis of the magnet and would, therefore, extend across the spindle of the 5 drag-element when such spindle is mounted as described in the hollow spindle, 3, said temperature compensating shunt has a central aperture, 5^b, large enough to encompass the spindle of the drag-element when it is 10 positioned as described within the spindle of the magnet, and to allow for all necessary movement of the shunt about its pivot which may be caused in the operation of the thermostatic temperature compensating device. 15 The mount, 2, has formed in it upon the side upon which the temperature compensating shunt, 5, is situated, an annular pocket, 2^c, which, however, need not be a complete annulus, that is may not extend all the way 20 around, and as shown does not completely encircle the axis. In this pocket there is lodged the thermostatic device, 6, which is a bi-metallic bar bent in a form nearly circular so as to be lodged in the annular pocket, 2^c, 25 one end of this thermostatic device (bi-metallic bar) being pinned fast to the mount by means of pin, 7, binding that end of said device in a seat which is provided for it, at one end of the incompletely annular pocket, 30 as in Fig. 2. The free end of the thermostatic bi-metallic bar is adapted for engaging the temperature compensating shunt, 5, by having a notch, 6^a, near the end, leaving standing at the end a small tooth, 6^b, which 35 engages a slot, 5^c, extending in the said shunt, 5, radially with respect to the pivot 40 of the shunt.

The segmental head, 5^a, of the shunt, 5, is 45 designed to lap at all times for a considerable portion of its width on one pole, and it has the edge toward the other pole cut obliquely in respect to the edge of said other pole so that as the shunt is moved or lapped on said other pole the initial lap occurs over 50 a triangular area, which increases from the inner angle of the triangle, as the shunt is moved, so that the increase and decrease of the area of the shunt lapped upon said pole changes gradually, the lap beginning with a 55 very minute area of the corner of the triangle, and increasing, not proportionately to the angular movement of the shunt about its pivot, but, at a rate which depends both upon that angular movement and the slope 60 of said oblique edge with respect to the proximate edge of the magnet pole. The form of this sloping edge, not only the angle of its slope but whether it shall be in a straight line or otherwise, is adapted to the 65 thermostatic device, that is, to the amount of

movement which that thermostatic device is adapted to give to the shunt for a given change of temperature within the range in which compensation is to be made, and thus said compensation can be made as accurate 70 as desired.

I claim:—

1. A tachometer magnet in the form of a split-ring in combination with an integral mount for the same of non-magnetic metal 75 occupying the central aperture and the gap of the said ring, the mount being flush with the lateral surfaces of the magnet at both sides.

2. In a tachometer a magnet in the form 80 of a split ring, in combination with an integral mount for the same of non-magnetic metal which occupies the central aperture of the magnet; a calibrating shunt plate held tightly to the mount at one side having a 85 segment which laps both poles to the magnet, and means for holding the shunt with its said segment tightly in lateral frictional contact with the magnet.

3. A tachometer magnet in the form of a 90 split ring in combination with an integral mount for the same of non-magnetic metal occupying the central aperture of the ring, the mount being flush with the lateral surfaces of the magnet at both sides, and a 95 calibrating shunt plate held tightly to the mount at one side, having a segment which laps both poles of the magnet, and means for holding the segment tightly in lateral frictional contact with the mount and mag- 100 net.

4. A tachometer magnet in the form of a split ring in combination with an integral mount for the same of non-magnetic metal occupying the central aperture of the mag- 105 net, said magnet having on one side a temperature compensating shunt, pivoted to the mount on that side, and lapping laterally on one pole of the magnet, and a thermostatic device connected to the mount and to the 110 shunt for swinging the latter about its pivot to cause it to approach and depart from, and to lap more or less on the other pole of the magnet.

5. A tachometer magnet in the form of a 115 split ring in combination with an integral mount for the same of non-magnetic metal occupying the central aperture of the mag- net, the mount being flush with the lateral surfaces of the magnet at both sides; a tem- 120 perature compensating shunt pivoted to the mount at one side of the magnet and lapping laterally on one pole thereof, and adapted to be moved about its pivot to lap upon the other pole, the mount having an annular 125 pocket in the side at which the shunt is pivoted; a thermostatic element lodged into the annular pocket and secured at one end of the mount and connected at the other end with the shunt for moving the latter about 130

its pivot by changes of temperature of said thermostatic element.

6. A tachometer magnet in the form of a split ring in combination with a mount for the same, occupying the central aperture of the ring; a temperature compensating shunt pivoted to the mount at one side of the magnet and lapping laterally on one pole thereof, and adapted to be moved about its pivot, 10 to lap upon the other pole, more or less; a thermostatic device attached at one end to the mount and having the other end engaging said shunt for moving the latter about its pivot, the edge of the shunt which is advanced for lapping upon said second men-

tioned pole of the magnet being oblique to the edge of said pole, whereby its lap upon said pole commences at one angle of a triangular area and increases by the movement of said triangular area onto the pole whereby the rate of increase of lap in a given movement of the shunt, caused by the thermostatic device, is governed by the form of said moving edge. 20

In testimony whereof I have hereunto set 25 my hand this 28 day of September 1914.

THEODORE J. FISCHER.
